SHORT WAVE TELEVISION TRANSMITTER

Kurt Schlesinger, Berlin, Germany, assignor, by
mesne assignments, to Loewe Radio, Inc., a
corporation of New York

Application April 20, 1936, Serial No. 75,403
In Germany April 30, 1935

3 Claims. (Cl. 178—7.1)

In the construction of short wave and ultra-short wave transmitters, which require to be modulated with very high modulating frequencies, there occurs again and again the problem of dynamically earthing in reliable fashion certain points of the connection system for the ultra-short carrier wave, and at the same time of impressing on the same points the high modulating frequency without the occurrence, by reason of the earthing elements in respect of the ultra-short wave, of an inadmissible load on the modulating circuits, and accordingly a drop in the maximum modulating frequencies. This problem can merely be solved incompletely with the usual blocking condensers, since in the first place the size of these condensers is limited in an upward direction by the fact that the same short-circuit the high modulating frequencies more and more and a large modulation output is required for generating the reactance currents by way of these condensers. On the other hand it is found in the short-wave art that merely a certain critical size of condensers, which is dependent on the self-inductions of the circuit to be earthed, really solves the problem of dynamic earthing, whilst both smaller as well as greater capacity values are completely ineffective dynamically, and by the formation of flywheel circuits may even lead to an oscillation of the particular potential point, i. e., may produce exactly the opposite to the desired effect.

The object of the following measures according to the invention is to solve in satisfactory manner the earthing problem and the combined problem of high-frequency earthing and low-frequency coupling with the modulator by the use of suitable series-resonance connections, auxiliary chokes and tuning condensers.

The novel features which I believe to be characteristic for my invention are set forth with particularities in the appended claims. My invention, however, both as to its organization and method of operation together with further objects and advantages thereof may be best understood by reference to the following description taken in connection with the accompanying drawings, which show two exemplary embodiments of my invention.

Fig. 1 shows a practical example as applied to simultaneous modulation and earthing. This refers to a three-grid modulation connection making use of a 5-electrode valve 1, which has already been explained in principle in the earlier specification Ser. No. 717,309. In this valve the cathode 2 is linked up with a counterpoise, for

example with the metallic mass of the casing 3. The innermost grid 4 is connected through the medium of a coil 5 with an exciting circuit 6. This circuit oscillates with half the frequency of the anode circuit 7. 6 is preferably a quartz oscillator, for example on the 14-metre wave. A detrimental coupling by way of the inner capacities of grid and anode and the assembly capacities is already reduced in the first order by the tuning of 7 to the 7-metre wave. The two remaining grids of the 5-pole tube 1, viz., the screening grid 8 and the so-called intercepting grid, or better, reflecting grid 9, belong to two other modulating circuits. The screening grid 8 is connected with the image-current amplifier 10, whilst the reflecting grid 9 is coupled with an impulse apparatus 11, which for the purpose of synchronisation produces sharp, negatively directed synchronisation impulses at the end of each line and image. The difficulty in the operation of this connection resides in practice in the fact that even in the case of valves, in which galvanometric dimensions have resulted in faultless operation of the grid control, a dynamic separation of the anode oscillation can not be successfully accomplished even with the strongest negative impulses of 10 or 11. To the contrary, even in the case of complete electronic blocking of the modulating valve 1, there always remains a considerable proportion of residual high-frequency potential in the anode circuit 7, which is conveyed by way of the coupling condenser 12 to the later output amplifying stages of the transmitter. This condition is also not affected by screening partitions 13 which may be introduced between the grid and anode circuits of the modulator 1. An inner capacitative coupling of the 5-electrode valve must accordingly be involved.

As a matter of fact experiments have shown that it is impossible to obtain neutralization with the aid of simple blocking condensers, which are shown in Fig. 1 in the form 14 or 15 for screening grid and reflecting grid. The short-circuit resistances of these condensers are not sufficiently small even in the case of assembly without loss, or a capacity amounting to several hundred centimetres would require to be introduced at these points, which in turn would load the generators 10 and 11 too strongly for their high frequency. According to the invention, a self-induction coil 16 or 17 is connected in each case in series with the earthing condensers 14 and 15. The condensers 14 and 15 are constructed as variable condensers, and their maximum capacity is se-

lected at less than 50 cm. The self-induction coils 16 and 17 are so dimensioned that they acquire series resonance at a medium capacity value of 14 and 15. In this connection, if the coils and condensers are built up without loss, a very low series resistance is produced which, as experiments have shown, solves the problem better than would be at all possible with a capacity alone. The capacitative load on the generators 11 and 10 is nevertheless smaller than when not using the resonance coils 16 and 17, as the capacities 14 and 15 merely require to be of approximately 20 cm. in capacity. There is conveniently provided a graduated scale on the condensers 14 and 15, as a readjustment thereof is required when altering the operating wave. In order to avoid a high-frequency reaction of the generators 10 and 11 on the short-circuits, it is necessary to connect a choke 18 or 19 in the leads to these generators. In place of the chokes there may also be used a resistance of not more than 500 ohms, so long as there is no inadmissible weakening of the high modulating frequency by reason of the potential distribution of the resistance then occurring against the capacities 14 and 15.

The feeding of the grids with bias takes place by way of series resistances 20/21, likewise behind the chokes 18 and 19. In this connection it may be remarked as follows: In the case of a 5-electrode valve according to Fig. 1 the screening grid 8 will be entirely without current when the reflecting grid 9 is traversed by a higher positive potential than the screening grid 8. In Fig. 1 this occurs by a tapping of the battery 22. By this measure it is accomplished that the control of the screening grid circuit 8 is successful without taking over current, i. e., without output. Certainly the bias of the intercepting grid 9 renders necessary a powerful negative amplitude of the impulse generator 11. To avoid this drawback it is also possible in accordance with the invention to apply the control circuit 19 to a special grid, which is provided between the reflecting grid 9 and the anode 7 and in turn possesses the potential of the cathode. The control of this grid then also occurs in wattless fashion. The reflecting grid 9 is then no longer modulated, but serves merely for suctional action on the electronic current, which otherwise would flow to the screening grid 8 and then load the image amplifying circuit 10/18.

In Fig. 2 there is shown such an embodiment of the invention, wherein 9' is the additional fourth grid lying between the reflecting grid 9 and the anode 7. The elements 23 and 24 represent the series connection of this additional grid for earthing the carrier oscillations. The element 25 performs the D.-C. connection to the cathode and earth respectively.

I claim:

1. In an ultra-short wave transmitter for television purposes a modulator comprising a multi-

electrode modulator valve having at least an earthed cathode, an anode, and three grids, an oscillation generator, a synchronizing impulse generator, and an image contents current generator, an oscillatory circuit in the anode circuit of said valve, each of said generators being connected to one of said grids, two series connections comprising each at least one condenser and one inductance so dimensioned as to be in series resonance with respect to the frequency of the oscillations of said oscillation generator, the two grids, which are next ones to the anode, being connected to the synchronizing impulse generator circuit and the image contents impulse generator circuit respectively and connected to earth by means of said series connections.

2. In an ultra-short wave transmitter for television purposes a modulator comprising a multi-electrode modulator valve having at least an earthed cathode, an anode, and four grids, an oscillation generator, a synchronizing impulse generator, and an image contents current generator, an oscillatory circuit in the anode circuit of said valve, each of said generators being connected to one of three of said four grids, two series connections comprising each at least one condenser and one inductance so dimensioned as to be in series resonance with respect to the frequency of the oscillations of said oscillation generator, three of said grids which are the next ones to said anode being connected to earth by means of said series connections, the first and the third of said grids numbered from the anode being connected to the synchronizing impulse generator circuit and the image contents impulse generator circuit respectively, the second grid numbered from the anode being supplied with a suitable positive bias potential higher than that of said third grid numbered from the anode, the first of said grids numbered from the anode having the same bias potential as the cathode and the fourth of said grids, numbered from the anode being connected with said oscillation generator.

3. In a short-wave or ultra-short-wave transmitter preferably for television purposes, a modulator comprising a multi-electrode modulator tube having an anode, a cathode and several interposed electrodes, a plurality of energizing circuits for supplying said interposed electrodes with short or ultra-short oscillations and modulation currents having frequency values up to very high frequencies to be modulated on said short or ultra-short oscillations, said electrodes supplied with modulation currents being connected to earth as regards said short or ultra-short oscillations by means of an inductance and a capacity connected in series as to form a series-resonant circuit resonating at said short or ultra-short oscillation, and being simultaneously connected to the modulation and bias sources respectively by means of chokes and resistances.

KURT SCHLESINGER.
